United States Patent Office

Des. 184,295
Patented Jan. 20, 1959

184,295

COMBINED BED AND LOCKER UNIT

Frank S. Wallen, Chicago, Ill., assignor to Superior Sleep-
rite Corporation, a corporation of Illinois

Application May 21, 1957, Serial No. 46,257

Term of patent 14 years

(Cl. D5—4)

Fig. 1

Fig. 2

Fig. 3

Figure 1 is a front perspective view of a combined bed and locker unit, showing my design;

Figure 2 is a rear perspective view; and

Figure 3 is a side elevational view thereof.

The dominant features of the design reside in those portions shown in full lines on the drawing.

I claim:

The ornamental design for a combined bed and locker unit, substantially as shown as described.
